DESIGN FOR A COMBINED MAGAZINE AND NEWSPAPER RACK OR SIMILAR ARTICLE

Louis E. Rubin, Lexington, Mass.

Application February 7, 1938, Serial No. 74,944

Term of patent 14 years

To all whom it may concern:

Be it known that I, Louis E. Rubin, a citizen of the United States, residing at Lexington, county of Middlesex, and Commonwealth of Massachusetts, have invented a new, original, and ornamental Design for a Combined Magazine and Newspaper Rack or Similar Article, of which the following is a specification, reference being had to the accompanying drawing, forming a part thereof.

In the drawing:

Fig. 1 is a front elevation of the rack showing my design; and

Fig. 2 is a cross-sectional elevation thereof, taken on the line 2—2 of Fig. 1.

I claim:

The ornamental design for a combined magazine and newspaper rack or similar article, substantially as shown.

LOUIS E. RUBIN.
